CLAIM

The ornamental design for a circular knitting needle box, as shown and described.

DESCRIPTION

FIG. 1 is a front elevational view of the circular knitting needle box showing my new design;

FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof; and,

In FIG. 7, the broken line showing of circular knitting needles are for illustrative purposes only and form no part of the claimed design.

FIG. 7 is a perspective view thereof.
